DESIGN FOR A LAPEL ORNAMENT

Joseph Carney, Miami, Fla.

Application August 9, 1944, Serial No. 114,800

Term of patent 3½ years

(Cl. D45—19)

To all whom it may concern:

Be it known that I, Joseph Carney, a citizen of the United States, residing at Miami, Florida, in the county of Dade and State of Florida, have invented a new, original, and ornamental Design for a Lapel Ornament, of which the following is a specification, reference being had to the accompanying drawing, forming a part thereof.

In the drawing:

Fig. 1 is a perspective view of a lapel ornament, showing my new design;

Fig. 2 is a rear elevational view;
Fig. 3 is a side elevational view; and
Fig. 4 is a top plan view of the same.

I claim:

The ornamental design for a lapel ornament, as shown.

JOSEPH CARNEY.
